LABEL DISPENSER

Carl G. Thiene, Pasadena, and Ray Stanton Avery, South Pasadena, Calif., assignors to Adhesive Development Co., a co-partnership consisting of Ray Stanton Avery and Dorothy Durfee Avery, Monrovia, Calif.

Application December 21, 1948, Serial No. 66,426

4 Claims. (Cl. 312—91)

1

This invention relates to a label dispenser. More particularly, it relates to a dispenser for dispensing labels which are adhesively mounted on a tape.

In label dispensers of the character referred to, a roll of tape is provided comprising the tape proper and spaced labels mounted upon and secured to the tape by means of a pressure-sensitive adhesive. It is desirable to peel the individual labels from the tape automatically and rapidly. In accomplishing this, it is not only necessary to feed the tape to a peeling mechanism, but it is also important to provide heat to facilitate the peeling action.

It is an object of the invention to provide an improved label dispenser of the character referred to.

It is a further object of the invention to provide a label dispenser of the character referred to which is capable of applying heat to the tape to facilitate peeling of the labels therefrom, and which is also capable of rapidly peeling the labels from the tape.

It is a still further object of the invention to provide a simple, easily constructed mechanism for peeling labels from tape and dispensing the same rapidly or slowly as desired, and which is simple in its operation and easy to adjust and maintain.

These and other objects of the invention will be apparent from the ensuing description and the appended claims.

One form which the invention may assume is exemplified in the following description and illustrated by way of example in the accompanying drawings, in which:

Fig. 1 is a top plan view, partly broken away to show certain of the interior parts, of the label dispenser of the invention.

Fig. 2 is a vertical, longitudinal section taken along the line 2—2 of Fig. 1.

Fig. 3 is a vertical section taken along the line 3—3 of Fig. 2.

Fig. 4 is a perspective view, on a smaller scale, of the dispenser.

Fig. 5 is a perspective view of the latch member.

Fig. 6 is a perspective view of the compressor plate.

Referring now to the drawings, a tape dispenser generally designated as 10 is housed in a housing 11 comprising a cover plate 12 and a base casting 13. Disposed within the housing is a motor 14 and speed reducer 14a and, as illustrated, a rheostat 15 is also provided. Also

2

shown are leads 16 leading to a foot switch (not shown) and power leads 17, which may be connected to any suitable source of electrical energy (not shown). An electric heating element 18 is also provided, being disposed in a recess 19 formed in the cover plate 12. The electrical circuits of the motor 14 and of the heating element 18 are not shown as they are conventional and form no part of this invention. The speed of the motor 14 is controlled by the rheostat 15. The heating element 18 is controlled by any suitable means (not shown). As illustrated, a master or toggle switch 20 is also provided and a pilot light 21 is provided to indicate when the power is on and the apparatus is in readiness for operation.

Referring now more particularly to Figs. 2 and 3 a hard rubber feed roller 30 having a grooved periphery 30a is provided. The feed roller 30 is fixed to a shaft 31 which is journaled in bearing brackets 32 depending from the cover plate 12. The feed roller 30 is driven by means of a sprocket 33 fixed to the shaft 31, a chain 34 and a sprocket 35 which is driven by the speed reducer 14a. A generally U-shaped guide member 36 is also provided, which extends from the feed roller 30 upwardly and then downwardly for a purpose explained hereinafter. A heating and stripping plate 40, which is advantageously formed of brass, copper or other highly heat-conductive material, is provided. The stripper plate 40 is secured to a countersunk portion of the cover plate 12 so that its upper surface will be flush with the cover plate, as illustrated, and, as will be seen, the stripper plate 40 is disposed directly above the heating element 16. The forward edge of the plate 40 is beveled at 41 as shown so as to form a rather blunt knife edge for peeling labels from the tape.

A front panel 42 is also provided, being hingedly supported upon the base casting 13 by means of a shaft 43 journaled in the base casting. The front panel 42 is of inverted L-shape, as illustrated, and it comprises a front portion 44 and a top portion 45. Secured to the underside of the top portion 45 by means of screws 46 is a compressor plate 47, which is slotted forwardly and rearwardly of its mid portion to provide fingers 50 and 51. The fingers 50 extend to beveled edge 41. As will be seen, the compressor plate 47 is bent downwardly so that it functions as a resilient or spring-like pressure member as and for a purpose explained hereinafter. The top portion 45 of the front panel 42 terminates in a vertical rib 52, which is similar to a rib 70

formed rearwardly of the front panel and is integral with the cover plate 12. The front panel 42 is also provided with a horizontal slot 53, which is disposed directly beneath the beveled edge 41 of the stripper plate 40 (when the panel 42 is in closed position). A guide roller 54 is journaled in the upper part of the front panel 42.

A latch member 55 is pivotally supported upon a shaft 56 extending between and journaled in opposite sides of the front panel 42. The latch member 55 comprises a handle portion 57, a front portion 58 and a guide and bracket portion 60. A guide roller 61 is supported upon a shaft 62, the ends of which are received in ovate slots 63 formed in opposite sides of the latch member, and springs 64 are provided to urge the roller 61 to its forward position as viewed in Fig. 2. That is to say, when the latch member 55 is in the position shown in Fig. 2, the springs 64 urge the roller 61 toward the guide member 36 and the feed roller 30. A guide member or guard 65 is also provided, extending, as illustrated, from the bottom of the bracket or guide portion 60 rearwardly and upwardly to a position just behind and adjacent the guide roller 61. As seen in Fig. 2, it will be noted that the axis of the roller 61 is above the axis 56 of the latch with respect to the axis of feed roller 30. Thus the spring will tend to keep the roller 61 in this upper position. However, when the latch handle 57 is raised, the roller 61 will be urged rearwardly against the tension of spring 64 and past the diametrically opposite point on the roller 30 from the pivot point 56 to a permit the roller 61 to be spaced from the guide 36 and the feed roller 30 when the tape is to be inserted.

Clamping members 71 are provided, each such member comprising a bail-shaped handle portion 72 and a dove-tailed foot member 73 received within and slideable in a dove-tailed groove 74 formed in the cover plate 12. Set screws 75 are provided for clamping the clamping members 71 in any desired position.

As illustrated, a roll of tape 80 having labels 81 adhesively secured thereto by a suitable pressure sensitive adhesive, is placed between the clamping member 71, which are adjusted so as to center the tape roll 80 and to support it loosely to allow unwinding.

In employing the device thus described, the power leads 17 are plugged in and the toggle switch 19 is turned to "on" position which results in lighting the pilot light 20 to indicate that the machine is in operating condition. A roll of tape 80 is mounted as described above, and the end of the roll is pulled outwardly, the front panel 42 being meanwhile in open position. A sufficient length of tape is unwound by hand and is creased under the beveled edge 41 of the stripper plate 40. In so creasing the tape, it is important that the crease be made in approximately the middle of a label.

The free end of the tape is then pressed inwardly so that it lies loosely against the hard rubber roller 30. The front panel 42 is then closed and the latch handle 57 is depressed to bring the latch member into its uppermost or latching position with its roller 61 abutting the guide member 36, as shown in Fig. 2. The rheostat 15 is then manipulated to operate the motor 14, hence the feed roller 30, at the desired speed. The feed roller 30 will now feed the tape upwardly between the guard member 36 and the guide roller 61, thence downwardly, where it is

guided by the guard member 36 to an opening 100 formed in the base casting. The machine may be placed on a table having a corresponding opening formed therein, and the waste tape allowed to drop through the opening in the base casting and in the table to waste receptacle.

Meanwhile, as the tape is being unwound, it will be heated by the heating element 16 as it passes over the stripper plate 40, thus facilitating peeling the labels, and the compressor plate 41 will press the tape firmly against the stripper plate. As the tape rounds the beveled edge 41 of stripper plate 40, each label will be peeled off and may be caught by hand or allowed to drop into a receptacle or conveyor belt (not shown).

It is thus apparent that a label dispensing machine has been provided which is simple and rugged in its construction, which is efficient in its operation, and which is readily controlled and easily adjusted.

While we have shown the preferred form of our invention, it is to be understood that various changes may be made in its construction by those skilled in the art without departing from the spirit of the invention as defined in the appended claims.

Having thus described our invention, what we claim and desire to secure by Letters Patent is:

1. A label dispenser, comprising a housing, means on the top of the housing for rotatably supporting a roll of laminated tape, a feed roller within said housing for feeding the lower lamina of the tape into said housing, means for rotating said feed roller, a stripper plate between said supporting means and said feed roller and disposed forwardly of both, whereby the lower lamina is forced to turn an acute angle in passing from the supporting means to the feed roller to create a condition for separating the laminae of the tape from one another, a rigid inverted generally L-shaped rearwardly facing cover plate pivotally mounted at the lower end thereof on the housing for pivotal movement about an axis below the feed roller and pivotal to an operating position where the upper leg thereof overlies the stripper plate and the tape thereon, said cover plate having spring means on the under side of said upper leg engageable with the tape to hold it firmly against the stripper plate, said cover plate also having an opening therein for the passage therethrough of the upper lamina of the tape, a stationary guide plate disposed adjacent to and rearwardly of the feed roller and providing a rearwardly facing concave portion against which the lower lamina is adapted to be held and along which the lower lamina is adapted to move upon rotation of the feed roller, and a latch pivotally mounted on the cover plate, carrying a resiliently mounted guide roller on the inner end thereof yieldably receivable in the concave portion of the stationary guide plate when the latch is pivoted to its operative position to simultaneously force the lower lamina against said concave portion and to latch said cover plate in operative position.

2. A label dispenser, comprising a housing, a stripper plate on the housing having a stripping edge, means on the housing for rotatably supporting a roll of laminated tape for supplying the tape to the top surface of the stripper plate from a point rearwardly of the stripping edge of said plate, a feed roller within said housing disposed below and rearwardly of the stripping edge of said stripping plate for feeding the lower lamina of the tape into the housing and causing the lower lamina

na to turn an acute angle around said stripping edge to create a condition for separating the laminae of the tape from one another, means for rotating said feed roller, a rigid inverted generally L-shaped rearwardly facing cover plate pivotally mounted at the lower end thereof on the housing for pivotal movement about an axis below the feed roller and pivotal to an operating position where the upper leg thereof overlies the stripper plate and the tape thereon, said cover plate having spring means on the under side of the upper leg thereof engageable with the tape to hold it firmly against the stripper plate, said cover plate also having an opening therein for the passage therethrough of the upper lamina of the tape, a stationary guide plate disposed adjacent to and rearwardly of the feed roller and providing a rearwardly facing concave portion against which the lower lamina is adapted to be held and along which the lower lamina is adapted to move upon rotation of the feed roller, and a latch pivotally mounted on the cover plate, carrying a resiliently mounted guide roller on the inner end thereof yieldably receivable in the concave portion of the stationary guide plate when the latch is pivoted to its operating position to simultaneously force the lower lamina against said concave portion and to latch said cover plate in operative position.

3. A label dispenser, comprising a housing, a stripper plate on the housing having a stripping edge, means on the housing for rotatably supporting a roll of laminated tape for supplying the tape to the top surface of the stripper plate from a point rearwardly of the stripping edge of said plate, a feed roller within said housing disposed below and rearwardly of the stripping edge of said stripping plate for feeding the lower lamina of the tape into the housing and causing the lower lamina to turn an acute angle around said stripping edge to create a condition for separating the laminae of the tape from one another, means for rotating said feed roller, a stationary guide plate disposed adjacent to and rearwardly of the feed roller and providing a rearwardly facing concave portion against which the lower lamina is adapted to be held and along which the lower lamina is adapted to move upon rotation of the feed roller, and a latch pivotally mounted on the housing forwardly of the feed roller, carrying a resiliently mounted guide roller on the inner end thereof yieldably receivable in the concave portion of the stationary guide when the latch is pivoted to its operative position to simultaneously force the lower lamina against said concave portion and to latch itself in operative position.

4. A label dispenser, comprising a housing, a

stripper plate on the housing having a stripping edge, means on the housing for rotatably supporting a roll of laminated tape for supplying the tape to the top surface of the stripper plate from a point rearwardly of the stripping edge of said plate, a feed roller within said housing disposed below and rearwardly of the stripping edge of said stripping plate for feeding the lower lamina of the tape into the housing and causing the lower lamina to turn an acute angle around said stripping edge to create a condition for separating the laminae of the tape from one another, means for rotating said feed roller, a rigid inverted generally L-shaped rearwardly facing cover plate pivotally mounted at the lower end thereof on the housing for pivotal movement about an axis below the feed roller and pivotal to an operative position where the upper leg thereof overlies the stripper plate and the tape thereon, said cover plate having spring means on the under side of the upper leg thereof engageable with the tape to hold it firmly against the stripper plate, said cover plate also having an opening therein for the passage therethrough of the upper lamina of the tape, electric heating means beneath the stripper plate for heating the tape pressed against the upper side of the plate, means for latching the cover plate in operative position, a stationary guide plate disposed adjacent to and rearwardly of the feed roller and providing a rearwardly facing concave portion against which the lower lamina is adapted to be held and along which the lower lamina is adapted to move upon rotation of the feed roller, and a pivotally mounted guide roller pivotal to a position in engagement with the concave portion of the stationary guide plate to press the lower lamina against said concave portion.
